UNITED STATES PATENT OFFICE.

CARL RÖHRS, OF LANDSBERG-ON-THE-WARTHE, GERMANY.

TUBULAR STEAM-BOILER.

No. 884,956.

Specification of Letters Patent.

Patented April 14, 1908.

Application filed May 29, 1907. Serial No. 376,225.

To all whom it may concern:

Be it known that I, CARL RÖHRS, a subject of the King of Prussia, residing at Landsberg-on-the-Warthe, in the Kingdom of Prussia 5 and German Empire, have invented a new and useful Improvement in Tubular Steam-Boilers, of which the following is a specification.

Steam boilers provided with several top shells, have heretofore been so constructed that the steam is conducted from the front shell through the middle shell or shells to the back shell and from thence back again to a special steam chamber in one of the middle shells. Such special steam chambers have however the drawback that access to the middle shell is rendered more difficult and that in order to clean the tubes by which the steam enters said shell the partitions forming such chamber have to be removed. 10 These drawbacks are overcome according to the present invention by causing the steam to pass from the foremost shell direct into the hindmost shell and from thence into the middle shell. By this construction a special steam chamber is rendered unnecessary, the cost is reduced and the safety of the boiler increased. 15

In the accompanying drawing illustrating 20 my invention: Figure 1 is a vertical section, and Fig. 2, a plan of one construction, and Fig. 3, a vertical section of another construction of the boiler.

The boiler shown in Fig. 1 consists of three 25 top shells A, B and C and two bottom shells D and E. Said top and bottom shells are connected with each other by nests of tubes F, G, H and J. Further the bottom shells D and E are connected together by a number of 30 tubes K and the water chambers of the top shells by a number of tubes L and M.

Fig. 3 shows a similar boiler, in which three 35 top shells are connected by the nests of tubes F, G, H with a single bottom shell D. In 40 this boiler the top shells are connected to-

gether in exactly the same manner as in the boiler shown in Fig. 1 and 2. Underneath the nests of tubes J in Fig. 1 and H in Fig. 3 is provided the grate P. The hot gases pass along the tubes in the direction of the arrows. 50 In the nests of tubes immediately over the grate steam is most vigorously developed, which in rising carries a large quantity of water into the top shell C. This wet steam does not pass direct into the middle shell as 55 in the boilers of this kind heretofore known, but enters the hindmost shell A through the pipe N. Here the steam loses its velocity, so that the heavier particles of water are deposited, whereupon the steam passes through 60 the pipes O into the middle shell B, the last particles of water being separated by the sharp edges of said pipes. The steam is taken from the boiler B through the socket S. When more than three top shells are used it 65 is immaterial which of the middle shells is connected with the hindmost shell.

What I claim and desire to secure by Letters Patent in the United States is:

1. A tubular boiler comprising three upper 70 shells and a plurality of lower shells connected with each other and with the upper shells, a steam pipe connecting the outer upper shells with each other, and a steam pipe connecting one of said outer shells with the intermediate 75 shell for the purpose set forth.

2. The combination with the grate, of a water shell arranged thereabove, a plurality of other water shells arranged behind the first shell and spaced apart therefrom, a water 80 connection between the shells, a steam connection between the foremost shell and the rearmost shell, and a steam connection between the rearmost and the intermediate shells.

CARL RÖHRS.
